UNITED STATES PATENT OFFICE.

THEODORE ROY DESJARDINS, OF ATTLEBOROUGH, MASSACHUSETTS.

DESIGN FOR A TABLE-CLOTH FASTENER.

SPECIFICATION forming part of Design No. 25,058, dated January 21, 1896.

Application filed November 29, 1895. Serial No. 570,561. Term of patent 7 years.

To all whom it may concern:

Be it known that I, THEODORE ROY DESJARDINS, of Attleborough, in the county of Bristol and State of Massachusetts, have invented and produced a new and original Design for a Table-Cloth Fastener, of which the following is a full, clear, and exact description.

Reference is to be had to the accompanying drawings, forming a part of this specification, in which—

Figure 1 is a plan view of a table-cloth fastener embodying my new design. Fig. 2 is a perspective view, and Fig. 3 is an inverted plan view.

The leading feature of my design consists

in the table-cloth fastener, comprising the top member *a* and the side members *b*, the latter ranging downwardly and being forwardly inclined, and having their lower parts in approximate parallelism with the top member *a*, said side members *b* further presenting at the forward ends of said lower parts diverging inner edges *c*.
